UNITED STATES PATENT OFFICE.

PAUL RISSMAN, OF DETROIT, MICHIGAN, ASSIGNOR TO FISHER BODY CORPORATION, OF DETROIT, MICHIGAN, A CORPORATION OF NEW YORK.

WINDOW-GUIDE.

1,378,558.

Specification of Letters Patent.

Patented May 17, 1921.

Application filed August 5, 1920. Serial No. 401,428.

To all whom it may concern:

Be it known that I, PAUL RISSMAN, a citizen of the United States, residing at Detroit, in the county of Wayne and State 5 of Michigan, have invented certain new and useful improvements in Window-Guides, of which the following is a specification.

This invention relates to window guides for closed body automobile construction and 10 has for its object a special form of window guide arranged to guide a sashless window and at the same time hold the same from rattling or breaking.

Furthermore, the guide has the capacity 15 of adapting itself to commercial automobile body glass of varying thicknesses, which is not true, so far as we are aware, in the conventional form of felted sashless window guides of the prior art.

20 In the drawings,—

Figure 1 is an inside elevation of a door of a closed automobile body.

Fig. 2 is a vertical section taken on the line 2—2 of Fig. 1.

25 Fig. 3 is a view of one end of the window well, fragmentary in character, and showing in elevation a pair of the rollers that serve as guides in the window well.

Fig. 4 is a section on the line 4—4 of 30 Fig. 2.

Fig. 5 is a section on the line 5—5 of Fig. 2.

Fig. 6 is a perspective of a portion of the guide channel.

35 Fig. 7 is a section on the line 7—7 of Fig. 2, and through the stile.

Fig. 8 is a section on the line 8—8 of Fig. 7.

40 Fig. 9 is a perspective of the lower window rest.

Fig. 10 is a fragmentary view of one side wall of the guide channel.

The usual present day construction for 45 closed automobile door windows embraces either a steel channel bar covered with felt to act as the side sash bar of the window or else a guide for a sashless window is provided, which is formed of a metal channel covered with felt or a similar material. In 50 this guide the sashless window is arranged to slide. However, this construction has to be built to accurately fit the glass, otherwise it isn't a success. If the glass varies in thickness, and there are several standard sizes, one size may fit too tightly in some of

the channel guides and other sizes fit too loosely. It is the object of the present invention to provide a new form of guide which not only eliminates this trouble due to variation of sizes in the commercial glass 60 but also to provide a guide in which the felt is located only inside of the channel and hence is not exposed to the weather so as to become discolored or torn.

A piece of sheet metal, such, for instance, 65 as phosphor-bronze, is taken and bent up into the configuration shown in Fig. 6. A single sheet forms the beads *a* and the channel *b* and the seating flange *c*. This construction can also be traced out in examining Fig. 7. In the side walls of the channel, pressed-in lips *d* are provided. An enlarged view of these is shown in Fig. 10, which is a mere fragment of the guide channel and which is a view looking at the inside of the 70 channel. It will be seen, from an examination of Fig. 10, that these lips are in the form of part-spherical knobs or heads *e* with necks *f*. The part-spherical or convex character of the heads of these spring lips 80 makes them present a smooth inclined surface to any sliding action of the glass in either direction in the channel.

These heads *e* project into the channel, as is clearly shown in Fig. 8, and bear against the 85 two thicknesses of felt *g* and *h* there shown. The inner thickness of felt *h* lines the channel while the outer thickness of the felt *g* is simply the felt that is doubled back over the wire *i* engaged in the bead *a*. It will 90 readily be seen that the felt may be assembled in the interior of the channel by doubling it back over a pair of wires and then forcing the wires into the beads through the mouths of the beads and then bending 95 the beads down over the wires so as to pinch them in place. It is not necessary to use the wires as the felt can be pinched directly in the bead. In this construction it will be understood that the felt is in no way exposed to the weather when the window is 100 closed. It is entirely concealed under the window, hence it is not much exposed to the sun or the elements which cause its early deterioration.

105 The seating flange *c* of the guide is nailed to the stile *j* of the door. On the face of the stile is bolted a strip or plate *k* which projects over the stile proper. A piece of sheet metal *l* is bent over this to form the usual 110

bead for the door. This is continued over the outer face of the stile and projects beyond the stile proper at the inside to form the shoulder or window stop *m*. It will be seen that the guide channel abuts directly up against this stop on the inside and that the beads of the guide channel project slightly beyond the same. The inside window stop is formed by the garnish molding *n* which can be applied directly over the flange *c* of the guide channel and is detachably secured to the stile by screws *o*.

By examining Figs. 4 and 7 it will appear that the window is sashless at the sides and also at the top. Of course, its bottom will be provided (except at the ends) with the usual retaining channel *p*, to which is attached the lifting strap *q* or to which may be applied the well known form of mechanical window regulator, which being no part of this invention is not here shown.

The special form of window guide above described has its channel considerably wider than the thickness of the glass. Inasmuch as the spring lips *d* project into the channel and press against the felt, this is calculated to take the standard thicknesses of glass varying from $\frac{1}{16}$ ths to $\frac{3}{32}$ nds of an inch and will take these without any alteration of the channel.

The construction of the stile in which the outer window stop is formed by folding over the sheet metal facing of the stile, effects a very material saving of lumber in large body building operations for it does away with the necessity of a recess about $\frac{3}{8}$ ths of an inch deep and saves about two feet of lumber to a stile.

Of course, it will be possible to continue the channel down not only the length of the window opening but also down through the window well, employing another section of channel for this purpose so as to permit of assembly. However, I prefer to use a plurality of rubber rollers *r* corrugated on their peripheries to make them more pliable and adjustable to the thickness of the glass. These rubber rollers are carried on studs *t* on plates *s* screwed to the stiles. These plates *s* also carry the small rubber buffers *u* which are let partly into the plates from the back. These buffers cushion the window at its edges to prevent it being thrown violently against the side of the stile to rattle or be broken. There is one rubber buffer used with each pair of rollers.

At the bottom of the window well is located a rubber socket or seat having a peculiar conformation, shown in Fig. 9.

The rubber socket piece is inclosed in a metal case *v* and is provided with a V-like opening at the top of the socket with a circular opening *w* at the bottom of the socket. These two openings are connected by a narrower passage and are divided by a pair of contact points or ribs *x* which have a spacing, at the outside, of $\frac{1}{16}$ ths of an inch and which are under-cut so that the spacing at the points *y* is $\frac{3}{32}$ nds of an inch. This forms a soft and pliable point of contact for the glass where the rubber block engages the same.

No claim is made in this application to the window guide construction in the window well as this is made the subject of another application of John T. Allmand, Serial No. 406,263, filed August 27, 1920.

What I claim is:

1. In closed body construction, a window guide in the form of a sheet metal channel provided with struck-in lips that are yieldable and portions formed at the opening of the channel for anchoring in combination with a felt lining for the channel anchored by said anchoring portions. 85

2. In a closed body construction, a window guide in the form of a channel of sheet metal provided with lips of a spring character struck in from the side wall of the channel and turned-over edges or beads at the edges of the channel in combination with a felt lining for the channel anchored in said beads. 90

3. In closed body construction, the combination of a channel member having lips struck in in the form of a part-spherical or convex head with a neck portion connecting with the body of the side wall, said lips having a spring character. 95

4. In closed body construction, a window guide in the form of a sheet metal channel provided with beads at the edges, felt lining the inside of the channel, and wires over which the felt is doubled and which are secured in the beads at the edges of the channel. 100

5. In closed body construction, a window guide in the form of a sheet metal channel having walls of spring material provided with struck-in lips at spaced points. 110

6. In closed body construction, a window guide in the form of a channel member formed of sheet metal of a spring character having struck-in and oppositely-directed lips at spaced points, for the purpose specified. 115

In testimony whereof I affix my signature.
PAUL RISSMAN.
